WITNESS.

UNITED STATES PATENT OFFICE

CARLO DI TOSTO, OF PATCHOGUE, NEW YORK

NECKTIE

Application filed August 15, 1929. Serial No. 385,988.

This invention relates to a necktie, the general object of the invention being to provide a hollow member which is adapted to be covered by the knot portion of the necktie and to which is also attached the upper end of the main flap or body of the tie so that the knot can be made of different material or a different color from the rest of the tie, with means carried by the member for holding therein portions of a band which is adapted to be passed around the neck and thus hold the necktie in position.

Another object of the invention is to provide means whereby the ends of the band can be inserted in the body or main flap of the tie.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a front view showing the parts assembled and in the position in which they are worn.

Figure 2 is a longitudinal sectional view through Figure 1.

Figure 3 is a view of the band.

Figure 4 is a rear view of the invention.

Figure 5 is a view of the wedge member.

Figure 6 is a perspective view of the hollow member on which the tie is formed with the upper portions of the sides thereof bent toward each other to provide a pocket for the wedge member.

Figure 7 is a side view of the member, prior to the bending of the upper portions of the sides thereof.

Figure 8 is a section on line 8—8 of Figure 1.

In these drawings, the numeral 1 indicates a hollow member which is of substantially channel shape in cross section and tapers from each end to the center, with the lower

portion rounded, as at 2. The sides of the member 1 have upper extensions 1' designed to be bent toward each other on fold lines 2' to provide a pocket for the wedge member which will hereinafter be described. The body or front A of the tie has its upper end covering the front or closed face of the member 1 and the side edges thereof. The upper end of the body A is arranged over the outer or top edge of the member 1 and is folded around the sides of the said member and has its said upper end inserted in the member. The knot forming portion B of the tie is passed around the upper portion of the member 1 and over the upper and outer portion of the body A and has the ends stitched together as at 4. There is now inserted in the member 1 a substantially triangular wedge member 5 shaped to fit the upper part of the said member 1. The parts 1' are bent toward each other, as disclosed by Figure 6 of the drawings for holding the wedge in the pocket thus provided in the member 1, and the confronting edges of the part B are stitched together. The wedge member 5 compresses the portions of the body A and the knot-forming portion B of the tie against the inner wall of the member 1. When the parts 1' are bent toward each other the wedge is held in the pocket provided therefor, but is susceptible to a downward movement in the said member 1 to engage with the portions of the necktie parts A and B with desired friction. A band or strip C is adapted to be passed around the collar of the shirt worn by the wearer, with its ends passing through the space formed by the member 1 and the wedge member 5 therein and the two portions of the band or strip are held against movement in the member 1 by the latch device 6 which is pivoted in the center of the member 1, as shown at 7, and has its end portions adapted to press portions of the strip C against the lower part of the member 1, as shown in Figures 2 and 4. The latch 6 is in the nature of a plate which is bent angularly upon itself and rounded at the said bent portion to provide an eye through which the pivot 7 passes and to likewise provide an upper or inner short arm 10 and an outer and

longer arm 11. The outer arm 11 is in the nature of a handle but both ends of the arms 10 and 11 contact with the neckband C as disclosed by Figure 2 of the drawings for 5 effectively holding the band when the latter is adjusted. Thus when the latch device is pressed inwardly, the strip C is held against movement so that the necktie will be properly supported in position. The extremities of 10 the strip C are passed within the folds of the part A of the necktie and the edges of these folds are then fastened together by a snap fastener or button 8, as shown in Figure 4.

A strip 9 of heavy material is placed in the 15 upper part of the body A to hold the same in shape, the upper end of this strip passing over the member 1.

Thus it will be seen that I have provided 20 means whereby a necktie can be easily and quickly adjusted on a collar without necessitating the tying and untying of the tie, which soon damages the tie, with means whereby the members 1 and 5 can be easily and quickly removed from one necktie and 25 attached to another tie. This invention also enables the knot portion of the tie to be formed of different material or material of a different color from that forming the body of the tie.

30 It is thought from the foregoing description that the advantages and novel features of the invention will be readily apparent.

It is to be understood that changes may be 35 made in the construction and in the combination and arrangement of the several parts, provided that such changes fall within the scope of the appended claims.

What I claim is:—

1. A necktie comprising a hollow member 40 tapering from each end to its center, a tie body provided with folds and having the upper portion thereof covering the front and sides of the hollow member, a knot forming portion covering the upper portion of the tie 45 body and the upper portion of the hollow member with the ends thereof secured together at the rear of said hollow member, said knot forming portion extending over one edge of said hollow member and disposed against the inner face thereof, a neck band having the ends thereof passing through the hollow member, a latch means for pressing portions of the neck band against the hollow member, a wedge member in the upper 55 part of the hollow member for clamping a portion of the knot forming portion in the hollow member, the free ends of the neck band entering the folds of the tie body, and means for connecting the edges of the folds together 60 to hold said ends of the neck band in place.

2. A necktie comprising a hollow member tapering from each end to its center, a tie body providing the front of a tie having the upper end thereof folded around the hollow member 65 and bent over one edge of said member and

inserted in the latter, a knot forming portion for the tie folded around the top portion of the tie body and around the top portion of the hollow member and having the ends thereof secured together and one edge folded into the top of the hollow member, a substantially V-shaped wedge member inserted in the hollow member for compressing portions of the tie body and knot forming member into said hollow member, a latch pivoted between the sides of the hollow member and having angle ends, and a neck band having its ends passed through the wedge and hollow member and contacted by the ends of the latch for holding the band to the hollow member.

In testimony whereof I affix my signature.

CARLO DI TOSIO.
